UNITED STATES PATENT OFFICE.

NATHAN I. STARK, OF PHILADELPHIA, PENNSYLVANIA.

SCOURING DEVICE.

Application filed October 2, 1926. Serial No. 139,162.

This invention relates to scouring implements, and more particularly to implements of the class used for cleaning kitchen utensils. The device, however, is not restricted 5 in its use and may be employed to advantage in many arts where a scouring operation is required.

The principal object of the invention is to provide a scouring implement which in general 10 is of simpler construction and more durable than devices of like nature previously developed.

A more specific object is to provide a holder for steel wool and the like having 15 novel and improved means for attaching and retaining said wool on the holder.

A further object is to provide, by novel means involving no positive mechanical connection, for retention of the steel wool or 20 other scouring medium against the working face of the holder, this provision permitting the use of small bodies of wool for scouring and thereby effecting a material saving of the scouring medium as hereinafter more 25 fully described.

In general, the invention contemplates the provision of an all-wood holder for steel wool or the like; the elimination of special or non-integral retaining means for the 30 wool; and means providing for the adherence of small bodies of the scouring medium to the holder with the novel result that the entire mass of said medium may be utilized.

In the attached drawings: 35 Figure 1 is a side view of a preferred form of holder embodying my invention;

Fig. 2 is a longitudinal section of the holder with a scouring body of steel wool attached, and

Fig. 3 is a bottom view of the holder.

With reference to the drawings, my device, in one form, comprises a suitably shaped body member having a part 1 constituting a handle or grip and terminating at one 45 end in a surface 2 which may be termed the working face. Obviously, the general shape of this member may vary widely and will depend largely upon the nature of the work for which it is intended. Obviously, 50 also, the shape and contour of the working face may vary; but for general purposes, this may consist of a flat surface of any suitable outline substantially free from irregularities.

In previous devices intended for the same purpose, it has been customary to secure

the steel wool or other scouring medium to the holder by means of special fastening means involving detachable or semi-detachable parts, usually of metal. I have discovered that by properly recessing the holder, as hereinafter described, and by forcibly pressing the edges or portions of a pad of steel wool or the like into said recesses, the said pad can be maintained in place on the holder without other securing means.

I have further discovered that by forming the working face with a higher coefficient of friction than that of the surface 70 which is to be scoured, there is a tendency for the steel wool to adhere to the surface of the holder, and that under these circumstances the holder may be used to pass the steel wool over a surface with no other 75 securing means than the frictional contact between the wool and the working face of the holder. Also the high coefficient of friction overcomes any tendency of the wool to pull out of the groove during the scouring 80 operation and prevents the strands of wool from shattering unduly by holding it firmly in position. The use of wood or similar relatively soft and non-metallic material for the holder accomplishes this desirable result. 85

In a preferred embodiment of my invention, and as shown in the drawings, the working face 2 is round, and the side of the device adjacent the working face is formed with a continuous recess 3 extending completely around the body of the device and with the center line of its mouth in a plane substantially paralleling the plane of the working face. The body of the device is so formed that the upper edge 4 of the recess 90 lies inwardly of the edge of the working face 2, the latter projecting outwardly appreciably beyond that part of the body immediately above the recess, as clearly illustrated. The recess for the purposes of the present 95 invention must be of considerable depth and comparatively narrow, and I have found that a recess $1/8$ " wide and substantially $3/8$ " deep is suitable.

In attaching a scouring pad of steel wool 105 to this holder, it is only necessary to lay the pad across the working face 2 and press the edges thereof firmly into the recess 3, as shown in Fig. 2. This may conveniently be done with the edge of a knife or any 110 blade-like implement. Preferably, the entire peripheral edge of the pad is entered

in the recess, and when applied as described and with a recess of proper proportions, the inserted portions remain firmly in place and offer considerable resistance to retraction.

5 Considerable importance is attached to the fact that the working face is of greater diameter and therefore extends outwardly beyond the immediately adjacent part of the holder. With this arrangement, there is no 10 tendency for the holder itself to come in contact with the vessel or article being secured, even after the steel wool at the sides has been worn thin. The device may be 15 freely manipulated over different surfaces with relatively slight danger of marring the surfaces by contact with the holder body. Also, as shown in the drawings, the working 20 face 2 is preferably slightly rounded out or convexed to more nearly conform to the curved surfaces of kitchen utensils.

In previously developed devices of this character, there has been an unavoidable 25 waste of steel wool or other scouring medium by reason of the inability of the device to utilize all parts of each particular mass or pad of the wool attached to the holder. By so forming the working face 25 of my device that the friction between the steel wool or other scouring medium 30 and itself will be greater than the friction between the wool and the surface to be scoured, I am able to utilize all parts of the pad down to the smallest remnants, since

under these circumstances there will be a 35 tendency for the wool to adhere to the working face of the holder in preference to the surface which is scoured.

As a general rule, it is undesirable to employ metal in a device of this character, and I have found wood to be well suited 40 to the purpose both for reasons of its desirable frictional characteristics previously set forth and also because of the cheapness and comparative simplicity of manufacture. Accordingly in its preferred form I make 45 the holder of an integral body of wood, the frictional advantages being present in the holding recess as well as at the working face. The device, however, need not be of integral construction, and in some forms a 50 non-integral construction may be found desirable. The invention, however, is not limited to the use of wood, since other materials, and particularly rubber or rubber compositions, may be used to advantage. 55

I claim:

A holder for steel wool comprising a handle-grip terminating in a working face and having in its side adjacent said face a continuous encircling recess of a width and 60 depth adapted to receive the compacted periphery of a steel wool pad for frictionally retaining the pad in position overlying said working face.

NATHAN I. STARK.
